UNITED STATES PATENT OFFICE.

ADOLPH M. HOLSTEIN, OF SYRACUSE, NEW YORK.

DESIGN FOR A MANUFACTURED FIGURE FOR FURNITURE, CASKET, INTERIOR OR EXTERIOR DECORATION.

54,319.

Specification for Design.

Patented Dec. 23, 1919.

Application filed August 22, 1917. Serial No. 187,567. Term of patent 3½ years.

To all whom it may concern:

Be it known that I, ADOLPH M. HOLSTEIN, a citizen of the United States, residing at Syracuse, in the county of Onondaga and State of New York, have invented a new, original, and ornamental Design for a Manufactured Figure for Furniture, Casket, Interior or Exterior Decoration, of which the following is a specification, reference being had to the accompanying drawing, forming a part hereof.

The drawing is an elevation or face view of this design.

This design comprehends the representation of a wreath formed at the base with

husks out of which extend flowers, leaves, twigs and buds, the wreath inclosing the representation of a sheaf of wheat tied with ribbons.

I claim:

The ornamental design for a manufactured figure for furniture, casket, interior or exterior decoration, substantially as shown and described.

In testimony whereof, I have hereunto signed my name, at Syracuse, in the county of Onondaga, and State of New York, this 30th day of July, 1917.

ADOLPH M. HOLSTEIN.
